BY ATTORNEY

UNITED STATES PATENT OFFICE.

ERNESTO PERUGGI, OF NEW YORK, N. Y.

DESIGN FOR A DOLL.

56,191.

Specification for Design. Patented Aug. 24, 1920.

Application filed June 7, 1920. Serial No. 387,191. Term of patent $3\frac{1}{2}$ years.

To all whom it may concern:

Be it known that I, ERNESTO PERUGGI, a subject of the King of Italy, residing at New York city, borough of Manhattan, in the county and State of New York, have invented a new, original, and ornamental Design for a Doll, of which the following is a specification, reference being had to the accompanying drawings, forming part thereof.

In the drawings,

Fig. 2 is a side view of the same.

I claim:

The ornamental design for a doll, as shown.

ERNESTO PERUGGI.
